Attorney

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 21, 1921. Serial No. 486,366.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to card-controlling 10 means for typewriting machines, and is in the nature of an improvement on the patent to Hellstrom, No. 970,708, granted September 20, 1910.

In inserting a stiff card around the cylindrical platen of a typewriting machine, the card tends constantly to bulge out from the platen and cause improper engagement between its ends and the ribbon, the ribbon-vibrator and the type-guide. Furthermore, 20 in a typewriting machine, as ordinarily equipped, it has been found impracticable to type upon the card near its top and bottom edges, due to inability to properly hold the card against the platen at the printing 25 line.

According to the above-mentioned patent, it was proposed to obviate such difficulties by providing flexible card-guides, attached 30 at their lower ends to a fixed part of the machine, and extending upwardly to engage the platen adjacent the ribbon-vibrator and type-guide, but on opposite sides thereof. Such card-guides were flared outwardly at 35 each of their side edges, and at their tops, so that a card would be directed thereunder if brought into engagement therewith, either from the top or the sides.

The main object of the present invention is to provide improved card-controlling 40 means for such general purposes, simple in construction, economical in manufacture, effective in operation, and easily applicable to machines of standard construction.

The present invention is particularly 45 adapted for use in writing on the last line of a card. In carrying out the invention, provision may be made of an aligning table so positioned on the platen-frame that a card

of the kind to be used will, when gaged thereon, be positioned with its last line at 50 the printing line. The card, when introduced at the front of the platen between the same and card-guides, such as disclosed in said patent to Hellstrom, may engage the ribbon or ribbon-vibrator, thus interfering with 55 the insertion of the card or work-sheet, or if the card has been properly introduced the ribbon or ribbon-vibrator, when lifted by the type-action, may catch on the lower edge of the card. To obviate such difficulties, 60 fingers secured to said card-guides extend inwardly over the flared side portions or lips of the card-guides, along the platen to points beneath the adjacent sides of the ribbon-vibrator and upwardly across the print- 65 ing line, and flared outwardly at their upper ends. It will be evident that the present invention clearly obviates any interference between the lower edge of the work-sheet and either the ribbon or ribbon-vibrator. 70

Other features and advantages will hereinafter appear.

In the accompanying drawings,

Figure 1 is a fragmentary front view, showing the invention as applied to so much 75 of an Underwood standard typewriter as is necessary for the purpose of illustration.

Figure 2 is a diagrammatic side view, partly in section.

Figure 3 is a view looking from above, 80 showing the position of the card-controlling devices with respect to the platen, the ribbon-vibrator and the type-guide.

Figure 4 is a fragmentary perspective view, showing the devices which co-operate 85 with the platen at the printing line.

Figure 5 is a fragmentary side view, showing the novel card-controlling fingers between the platen and the ribbon-vibrator.

The platen 11 is supported by an axle 12 90 journaled in the ends 13 of a platen-frame 14 comprising the usual rear paper-table 15. Positioned above the platen is an aligning table 16 provided with a side-edge gage 17 and a leading-edge gage 18. The table 16 95 is secured to a bar 19 extending across the

2. platen-frame by screws 20 extending through slots 21 in the table and threaded into the bar 19. The slots 21 are provided with countersunk portions 22 around their edges to receive the heads of the screws 20, so that the tops of the heads will lie beneath the surface of the table 16. The screw-and-slot connections between the table 16 and the bar 19 enable the table 16 to be trued up with reference to the printing line, and said connections may be used for adjusting the distance of the leading-edge gage 18. At its ends, the bar 19 is attached by suitable means, such as screws 23 having knurled heads for convenience in turning the same, to brackets 24 secured to the ends of the platen-frame by suitable means, such as screws 25.

The position of the table 16 is determined by the card 26 to be used in connection therewith, the last line of which, when the card is gaged by the leading-edge gage or flange 18, will lie at the printing line. To detain the card in this position, provision may be made of spring-clips 27 fastened to the bar 19 at its back by suitable means, such as screws 28.

Fixed on the usual type-bar segment 29 is a type-bar guide 30, and slidably mounted between the guide 30 and the platen is a ribbon-vibrator 31 by which a ribbon 32 is lifted to the printing line upon actuation of any one of the types 33 mounted on type-bars 34, so that the types may strike there-through and print on the surface of the card supported by the platen.

To hold the card against the platen at the printing line, provision may be made of flexible guides 35 secured to the segment 29 by suitable means, such as screws 36, and engaging the platen at the printing line. Each of these guides has outwardly-flaring lips 37 and 38 at its inner and outer edges, respectively, and an outwardly-flared lip 39 at its upper end. It will be evident that the lips 37 and 38 will tend to carry the edge of the card brought thereagainst by movement of the platen, under the guide of which the lip forms a part, and that the outwardly-flared lips at the upper ends of the guides 35 tend to direct the lower edge of a card inserted at the front of the platen between the latter and the guides 35.

Each guide 35 is provided with an aperture 40 which is rectangular and extends for nearly the entire width of the guide. The lower edge 41 of each aperture 40 is substantially in register with the printing line on the platen, and both of the lower edges taken together may be made to serve as a means to enable the operator to square the leading edge of the card to the writing line, or to adjust any desired line on the card in register with the writing line on the platen. Each guide is also provided with gradu-

tions 42 in proximity to the edge 41 to register with the type impressions upon the platen, said graduations being at letter-space intervals.

Although the card-guides 35 are designed to hold a stiff card in proper position relative to the platen, it will be evident that, when a card 26 is inserted at the front of the platen, the lower edge of the card may engage the ribbon or ribbon-vibrator, and that in case the lower edge of the card is positioned substantially at the printing line, as shown in Figures 1 and 2, the upward movement of the ribbon-vibrator may cause the vibrator itself or the ribbon 32 to engage the lower edge of the card. To obviate these difficulties, provision may be made of fingers 43 secured to the guides 35 along their front faces, carried over the lips 37 and extended along the platen to positions between the adjacent sides of the ribbon-vibrator and the platen, and having upright extensions 44 extending across the printing line. The upper ends of the uprights 44 may be flared outwardly at 45 so as to facilitate the front insertion of the card 26. It will be evident that the fingers 43 with their uprights 44 render it substantially impossible for interference to arise between the lower edge of the card and either the ribbon or ribbon-vibrator, even when the platen is shifted up and down to enable the different sets of types to print.

Inasmuch as the aligning table is intended to be maintained in one position and it may be desirable to position the card or work-sheet 26 so that lines, other than the last, may be placed at the printing line, provision may be made of lines 46 on the table at line-space distances from the gage 18. The leading edge of the card may then be gaged in connection with gage 18 or one of the lines 46, as desired. It will be seen that the clips engage the table 16 at such points that they will detain the cards 26 on the table, whether gaged by gage 18 or by the lines 46.

In use, the card 26 may be inserted at the front of the platen, its lower edge being guided by the lips 39 between the platen 11 and the guides or fingers 35, and also, by the flared portions 45 at the upper ends of the extensions 44, between the platen and the ribbon-vibrator.

It will be noted that in a front-strike typewriting machine having a platen frame and a revoluble platen, and having a ribbon-vibrator in front of the platen, that I have provided a novel card holding and guiding organization including a card-shelf arranged on edge above the front of the platen and supporting the card in flat condition in a position tangential to the platen at the printing line and inclined but slightly back from the vertical to clear the

upper set of the types 33 without appreciably bending the card, Figure 2; a leading-edge gage on said card-shelf positioning the card with its bottom edge substantially coincident with the bottom of the printing line on the platen, a pair of upright card-guiding members 35 secured upon the machine frame and having flared edges and extending across the printing line, and a pair 5 of card-guiding fingers 43 extending from said upright members laterally back of the adjacent sides of the ribbon-vibrator and then upwardly at 44 beyond the upper edge of the vibrator and across the printing 10 line and holding the lower edge of the card against the platen to receive the type impressions, and preventing interference between the lower edge of the card and the ribbon-vibrator during typing, said upright 15 members and said fingers extended up sufficiently to maintain control of the card when the platen and card are shifted up in the usual manner to receive the impressions of the upper set of the types 33. 20

25 Variations may be resorted to within the scope of the invention, and portions of the improvements may be used without others.

Having thus described my invention, I claim:

- 30 1. In a front-strike typewriting machine having a platen frame and a revoluble platen, and having a ribbon-vibrator in front of the platen, card holding and guiding means including a card-shelf arranged 35 on edge above the front of the platen and supporting the card in flat condition in a position tangential to the platen at the printing line and inclined but slightly back from the vertical to clear the upper set of 40 types without appreciably bending the card, a leading-edge gage on said card-shelf positioning the card with its bottom edge substantially coincident with the bottom of the printing line on the platen, a pair of upright 45 card-guiding members secured upon the machine frame and having flared edges and extending across the printing line, and a pair of card-guiding fingers extending from said upright members laterally back of the adjacent sides of the ribbon-vibrator and then upwardly beyond 50 the upper edge of the vibrator.
- 55 2. In a front-strike typewriting machine having a platen frame and a revoluble platen, and having a ribbon-vibrator in front of the platen, card holding and guiding means including a card-shelf arranged on edge above the front of the platen and supporting the card in flat condition in a position tangential to the platen at the printing 60
- line and inclined but slightly back from the vertical to clear the upper set of types without appreciably bending the card, a leading-edge gage on said card-shelf positioning the card with its bottom edge substantially coincident with the bottom of the printing line on the platen, a pair of upright card-guiding members secured upon the machine frame and having flared edges and extending across the printing line, and a pair of card-guiding fingers extending from said upright members laterally back of the adjacent sides of the ribbon-vibrator and then upwardly beyond the upper edge of the vibrator. 65
- 70 3. In a front-strike typewriting machine, in combination, a platen, a ribbon-vibrator, two upright members secured at their lower ends to a fixed part of the machine and extending across the printing line to co-operate with the platen at opposite sides of the ribbon-vibrator to hold a work-sheet against the platen, each of said upright members being flared forwardly at its edges to guide the edge of the work-sheet to the rear thereof, and means to hold the work-sheet against the platen at the rear of the ribbon-vibrator to prevent interference between the lower edge of the work-sheet and the ribbon-vibrator and ribbon therein, said preventing 75 means comprising fingers secured to said members at their outer ends and extending inwardly back of the adjacent sides of the ribbon-vibrator and then upwardly beyond the upper edge of the vibrator. 80
- 85 4. In a front-strike typewriting machine, the combination with a revoluble platen, of a platen-frame, a ribbon-vibrator, a device for enabling the typing of a card in the last printing line position at the bottom thereof, while the card is held in a substantially flat condition, comprising a gage-plate upon which to place the card, detachable bracket members mounted up from the platen-frame to support the gage-plate at a suitable elevation above the platen on its delivery side, and spring clips bearing on the gage-plate mounted on the bracket members to hold the top portion of the card on the gage-plate so as to locate its bottom portion in precise typing position at the printing point, and co-operative means to engage the bottom edge of the card, comprising two upright members, one on each side of the printing point, secured at their lower ends to a fixed part of the machine, each upright member 90

having flared edges to guide the card and a finger secured to each of said upright members and extending back of the adjacent sides of the ribbon-vibrator and then upwardly beyond the upper edge of the vibrator to hold the lower portion of the card against the platen to receive the type im-

pressions, and to prevent interference between the lower edge of the card and the ribbon-vibrator during typing.
